(57) **CLAIM**

I claim the ornamental design for a rescue stretcher, as shown and described.

DESCRIPTION

FIG. 1 is a top side perspective view of a rescue stretcher in a tensioned and operative configuration.

FIG. 2 is a side elevation view of the rescue stretcher of FIG. 1

FIG. 3 is front perspective view of the rescue stretcher of FIG. 1 in a flat and relaxed configuration with a number of securement straps shown in a latched configuration; and, FIG. 4 is a top plan view of the rescue stretcher of FIG. 1 in a flat and relaxed configuration with the securement straps shown removed. The bottom view is a mirror image thereof. In FIGS. 1 and 2, the dashed lines showing a person secured in the rescue stretcher illustrate an environment that forms no part of the claimed design.
